UNITED STATES PATENT OFFICE.

EDWARD ERICKSON, OF WEST LYNN, MASSACHUSETTS, ASSIGNOR, BY DIRECT AND MESNE ASSIGNMENTS, TO VICTOR SHOE MACHINERY COMPANY, OF BOSTON, MASSACHUSETTS, A CORPORATION OF MASSACHUSETTS.

PRESSER-FOOT MECHANISM FOR SEWING-MACHINES.

1,151,768.

Specification of Letters Patent. Patented Aug. 31, 1915.

Original application filed August 18, 1911, Serial No. 644,769. Divided and this application filed December 4, 1911, Serial No. 663,940. Renewed February 18, 1915. Serial No. 9,207.

To all whom it may concern:

Be it known that I, EDWARD ERICKSON, a citizen of the United States, and a resident of West Lynn, in the county of Essex and State of Massachusetts, have invented certain new and useful Improvements in Presser-Foot Mechanism for Sewing-Machines, of which the following is a specification.

10 This invention relates to machines for sewing heavy material such as leather, and refers particularly to the mechanism for controlling the presser foot of that type known as welt sewing machines.

15 The object of the invention is to provide an improved mechanism which will effect the locking of the presser foot to hold the work tightly during the formation of each stitch, and to release it during the feed of the work.

20 To this end the present invention consists in the construction and combination of parts, substantially as hereinafter described and claimed.

25 Of the accompanying drawings,—Figure 1 is a front elevation of the machine complete. Fig. 2 is an elevation from the left of Fig. 1. Fig. 3 is an elevation from the right of Fig. 1. Fig. 4 represents a section 30 on line 4—4 of Fig. 1, and Fig. 5 represents a detail, partly in section on line 5—5 of Fig. 4.

35 In the present application only the presser foot mechanism will be described but for the description and operation of the entire lock-stitch sewing machine reference may be made to my application 644,769, filed Aug. 18, 1911, of which the present application is a division.

40 The same reference characters indicate the same or similar parts in all of the views.

45 In the embodiment of the invention illustrated, the base 30 is formed or provided with two uprights or standards 31, 32, having bearings for a lower main or drive shaft 33 and an upper counter shaft 37 and a fixed shaft 38 on the latter of which are mounted certain parts for operating the shuttle 53. The main shaft has a pulley 34 for a power 50 driving belt, and has a crank 35 intermediate its ends, to which crank is connected one end of a pitman 36 for actuating the awl 137 and needle 121 said awl and needle

in their movements being adapted to pass through a slot 66 in the work support 67 55 with which a presser foot 71 coacts.

The work presser comprises an arm 71 having a foot 72 (Figs. 1, 2, 3 and 4) to bear on the work supported by arm 67, said arm having a hub 73 mounted on a 60 stud 74 supported by standard 32. An arm 75 projecting rearwardly from the hub 73 is provided with a toothed segment 76 which meshes with a pinion 77 (Fig. 4) fast on rock shaft 78.

To effect the locking of the presser foot to hold the work tightly during the formation of each stitch, and to release it during the feed of the work, the following mechanism is provided:—Secured to arm 75 is a 70 segment rack 86, meshing with a pinion 87 having a sleeve hub 88 mounted on a crank or wrist pin 89 (see Fig. 5 in connection with Fig. 4) of a stud rock shaft 90 mounted in standard 32 and carrying an arm 75 91 at its outer end. The arm 91 has a roll 92 engaging a cam groove 93 in a disk 94 secured to shaft 33, said cam groove being indicated by dotted lines in Fig. 4. On the wrist pin 89, at the outer end of sleeve hub 80 88, is a collar 95 having a ratchet-toothed outer end face 96 engaged by a pin 97 projecting from said wrist pin. A spring 98 is coiled around, and has its ends connected to, the collar and hub so as to constitute a yielding connection between said two members 85 and consequently to cause the presser foot to bear yieldingly on the work with a pressure that may be varied by adjusting the collar rotatively, the desired adjustment being maintained by the pin 97 engaging one of the end teeth of the collar. Such yielding pressure however ceases when the awl 90 is penetrating the work. To interrupt this yielding pressure and cause the presser foot 95 to remain immovably in position to resist the force of the upwardly moving awl, I provide means for preventing rotation of the pinion 87 at the proper time. Mounted on the hub 88 are two collars 99 and 100, 100 said collars inclosing a spring 101 which snugly fits the hub and has its two ends connected to the two collars so that relative rotation of the collars will tighten the spring on the hub to act as a clutch brake on the latter, 105 or release it. The collar 99 has an arm 102

provided with a slot which receives a fixed pin 103, whereby said collar is prevented from rotating although it presents no obstruction to the lateral movement of the pinion hub 88 when the wrist pin is shifted. The other collar 100 has an arm 104 connected by a link 105 with a lever 106 fulcrumed on a stud 107 and having a roll 108 engaging a cam groove 109 in disk 94. This arm 104 is moved downwardly by the cam groove 109 when it is desired to tighten the brake spring. Pivoted to the lever 106 at 110 is an arm 111 having a roll 112 engaging the outer surface of the rib which forms the outer wall of cam groove 109. The other end of the arm 111 is formed or provided with a yoke 113 which embraces an eccentric 114 (see dotted lines in Fig. 4) which is mounted on stud 107 and has an arm 115 which enters a notch 116 in a vertically movable bar 117 that is adapted to be lifted manually, as by a suitable treadle, not shown. When the parts are in the position shown in Fig. 4, the two rolls 108, 112, follow the cam rib and cause the lever 106 to be so actuated that the collar 100 is rotated sufficiently to tighten the brake spring 101 and prevent the presser foot from yielding excepting at the end of the feed movement. The gripping effect of the coiled brake spring 101 is obtained regardless of the thickness of the work. That is, when the presser foot is lifted for the introduction of work and then descends upon the work under the pressure of spring 98, it may occupy a higher or a lower position according to the work. But the grip to hold it there will be just as effective whether the work be thick or thin.

40 The hub 73 of the presser foot arm or lever is provided with an arm 118 having a pin 119 which projects across the top of bar 117. When the bar 117 is lifted, as when work is to be introduced, the action 45 on arm 118 is such as to raise the presser foot 72. Before this, however, the arm 115 is actuated so as to rock the eccentric 114 and swing arm 111 to throw the roll 112 outwardly and then as the cam disk 94 rotates, 50 a recess 120 in the inner wall of cam groove 109 comes to a position opposite roll 108 so as to relieve outward pressure on said roll and thus release the braking effect of spring 101 and permit the presser foot to 55 be lifted by the further upward movement of bar 117. When the bar 117 is lowered again, a projection 117^x (Fig. 4) therefrom engages the stud at the outer end of arm 115 and insures the return of said stud into the 60 notch 116.

The presser foot is positively lifted slightly (about one-sixteenth of an inch) during each feed operation. This is when the roll 92 of arms 91 is in the position indicated in Fig. 6. As the sleeve hub 88 is eccentric to

the axis of stud 90 which carries arm 91, movement of arm 91 toward said position swings said hub 88 laterally. At this time, the brake spring 101 is holding pinion 87 locked so that the said lateral movement of 70 the pinion 87 acts through the rack 86 to oscillate the arm 75 and raise the foot 72 slightly but positively, so that the work can be fed freely by the awl.

A spring 101 is coiled upon the hub 88 of 75 pinion 87 in such direction that, as it is tightened to apply a braking action, it tightens in such direction as to add its force to that of spring 98, which latter spring causes the presser foot to bear yieldingly 80 upon the work. This additional force applied to the presser foot by the tightening of the spring 101 is due to the increased frictional contact of said spring with the periphery of the hub 88 which tends to rotate said hub in the direction that the spring 101 is being wound, this direction corresponding to the direction that the tension of the spring 98 acts. This additional pressure continues to be increased until the arm 85 104 comes to a rest at the end of its downward movement. The momentary addition of the force of spring 101 to that of spring 98 causes the presser foot to bear more heavily upon the work just before the locking occurs due to the complete binding of the brake spring 101 upon said hub. This action, however, does not interfere with the lifting of the presser foot to permit the awl to feed when the crank-mounted stud 89 is 100 moved by the actuation of the arm 91. The arm 91 is actuated at the proper time to cause the stud 89 to shift about the axis of the stud shaft 90 to which said arm 91 is connected, to cause the presser foot to be 105 lifted to permit the awl to feed the work. This provision enables the work to be properly fed by the awl, even when the stock is soft. Consequently, the work when being fed does not have to be pulled along by the 110 awl against the resistance of any spring pressure whatever applied to the presser foot.

I claim:—

1. Presser foot mechanism for sewing machines comprising in combination a lever having a presser foot and a segment rack, a pinion meshing with said rack, means for yieldingly actuating the pinion to cause the foot of said lever to bear yieldingly on the work after the completion of the feed, means for holding the lever rigidly during other operations, means for positively lifting the presser foot during each feed operation, a manually operable presser-foot lifter, and connections for releasing the lever holding means when said manually operable lifter is actuated.

2. Presser foot mechanism for sewing machines comprising in combination a lever 130

- having a presser foot and a segment rack, a pinion meshing with said rack, means for yieldingly actuating the pinion to cause the foot of said lever to bear yieldingly on the work after the completion of the feed, a 5 brake device to hold the lever rigidly at predetermined times, means for positively lifting the presser foot during each feed operation, means for bringing said brake device into operation when the awl is penetrating the work, a manually operable presser-foot lifter, and connections for releasing the brake when said manually operable lifter is actuated.
- 10 3. Presser foot mechanism for sewing machines comprising in combination a lever having a presser foot, a toothed segment carried by said lever, a pinion in permanent engagement with said segment and provided with a lateral hub, a spring for yieldingly opposing rotation of said pinion in one direction, a brake spring coiled on the hub of 15 said pinion, and means for intermittently tightening said brake spring, consisting in 20 part of two collars loosely mounted on said hub and to each of which an end of said spring is connected.
4. Presser foot mechanism for sewing machines comprising in combination a lever 25 having a presser foot, a toothed segment carried by said lever, a stud having a sleeve mounted on it, said sleeve having a pinion in permanent engagement with said segment, a collar adjustably mounted on said 30 stud, a brake spring coiled on the hub of said pinion, and means for intermittently tightening said brake spring.
5. Presser foot mechanism for sewing machines comprising in combination a lever 35 having a presser foot, a toothed segment carried by said lever, a stud shaft having a crank pin, a sleeve mounted on said crank pin and having a pinion engaging said segment, a spring for yieldingly opposing 40 rotation of the sleeve and pinion, an arm con-
- nected to said stud shaft, and means for oscillating said arm and stud shaft.
6. Presser foot mechanism for sewing machines comprising in combination a lever having a presser foot, a toothed segment 50 carried by said lever, a crank-mounted stud having a sleeve mounted on it, said sleeve having a pinion engaging said segment, brake mechanism for positively preventing rotation of the sleeve in either direction at 55 predetermined times, and means for intermittently changing the position of the crank-mounted stud.
7. Presser foot mechanism for sewing machines comprising in combination a lever 60 having a presser foot, a toothed segment carried by said lever, a stud having a sleeve mounted on it, said sleeve having a pinion engaging said segment, two collars mounted on said sleeve, a spring surrounding the 65 sleeve and having its ends connected to the two collars, and means for actuating one of said collars to tighten the spring on the sleeve and prevent its rotation at predetermined times.
8. Presser foot mechanism for sewing machines comprising in combination a lever 70 having a presser foot, a toothed segment carried by said lever, a crank-mounted stud having a sleeve mounted on it, said sleeve having a pinion engaging said segment, brake mechanism for positively preventing 75 rotation of the sleeve in either direction at predetermined times, means for intermittently changing the position of the crank- 80 mounted stud, and means for manually releasing the brake and lifting the presser foot.

In testimony whereof I have affixed my signature, in presence of two witnesses.

EDWARD ERICKSON.
